United States Patent Office

Des. 222,309
Patented Oct. 12, 1971

222,309

DISPLAY STAND

Donald H. Ellingson and Herbert L. Reynolds, Seattle,
Wash., assignors to Reynolds Display-Fixtures Inc.,
Seattle, Wash.

Filed June 4, 1970, Ser. No. 23,319

Term of patent 14 years

Int. Cl. D6—06

U.S. Cl. D80—9

FIG. 1 is a top plan view of a display stand showing our new design.

FIG. 2 is a front elevational view thereof, the rear being flat and unornamented.

FIG. 3 is a side elevational view thereof.

FIG. 4 is a front top perspective view thereof.

FIG. 5 is a top plan view of a modified form of the display stand shown in FIG. 1.

FIG. 6 is a front elevational view of FIG. 5, the rear being substantially flat and unornamented.

FIG. 7 is a side elevational view of FIG. 5.

FIG. 8 is a front top perspective view of FIG. 5.

We claim:

The ornamental design for a display stand, substantially as shown and described.
